UNITED STATES PATENT OFFICE.

THOMAS J. LOVETT, OF CHICAGO, ILLINOIS, ASSIGNOR TO THE CHICAGO
ORDNANCE CO., OF CHICAGO, ILLINOIS, A CORPORATION OF ILLINOIS.

BUILT-UP GUN.

SPECIFICATION forming part of Letters Patent No. 690,066, dated December 31, 1901.

Application filed July 16, 1898. Renewed July 12, 1901. Serial No. 67,974. (No model.)

To all whom it may concern:

Be it known that I, THOMAS J. LOVETT, a citizen of the United States, residing at Chicago, in the county of Cook and State of Illinois, have invented a new and useful Improvement in Ordnance, (for which I have received Letters Patent of the Kingdom of Belgium, No. 137,324, dated August 10, 1898, and in Austria, No. 48/4,861, dated October 1, 1898,) of which the following is a specification.

My invention relates to improvements in ordnance construction, and more particularly to improvements in cannon of the built-up type.

15 My object is to provide a composite cannon so constructed that it may be readily taken apart and put together again in the field, if desired, to renew parts which may have become injured and to render its transportation 20 from place to place, and to locations where the cannon if in one piece could not be carried, comparatively easy to accomplish.

My object is also to provide a construction 25 of ordnance wherein the gun is practically free from the danger of crystallization following the terrific concussive force of modern high-power explosives.

It is a well-known fact that guns made of steel as hitherto constructed and subjected 30 in the making to the most careful treatment will in a comparatively short time be injuriously affected by the jarring action of the discharge to such an extent as to render their further use unsafe. It appears that the very 35 high elasticity of the steel, especially where the fibers thereof extend longitudinally of the gun, by readily transmitting the shocks, contributes to render certain and quick the molecular change in structure of the steel, 40 known as "crystallization," which ruins the gun.

In the accompanying drawings, Figure 1 is a side view of a dismounted gun embodying my invention; Fig. 2, a longitudinal section of the gun; Fig. 3, a front elevation of one of the rings or annuli of the construction I prefer to employ in forming the gun; Fig. 4, a view of a modification of the inner tube employed; and Fig. 5, a rear elevation

of one of the annuli, showing it provided 50 with perforations to receive bolts or securing-rods.

In the construction shown in Fig. 2, A is an inner tube extending the full length of the gun and provided throughout its length 55 with an external screw-thread. Internally the tube may be rifled.

B and C are sections or annuli, which make up the largest bulk of the gun-body and are preferably formed as hereinafter described. 60 The sections B each consist of an inner ring *t*, an outer ring *r*, and an intermediate ring *s*. The rings *t* *r* are formed, preferably, of steel, cut or stamped from rolled and treated plates or formed from bars shaped and welded together at the ends. The ring *r* is formed, preferably, of a non-elastic shock-deadening material, which may be asbestos prepared with a suitable binding and compressed to the required solidity. The inner rings *t* are internally threaded to fit the thread of the inner tube A, and the outer rings *r* are formed on one side with annular projecting flanges *r'*, internally threaded, and on the other side with threaded sockets *r''*, as shown. The sections C are of steel, formed with threaded flanges and sockets, like the rings *r*, and internally threaded, like the rings *t*, to fit the thread of the tube A. The sections are fitted together as shown in the drawings, the 70 threads on the flanges *r'* and reduced or socket portions *r''* being of the same pitch as the thread upon the tube, whereby the sections 75 may be turned upon the tube in placing them in position and will readily match together. 80 The gun thus built up will resist all danger 85 of sagging at any part.

The barrel may be mounted in any suitable manner. I have shown it provided with trunnions D, projecting from a ring D', suitably 90 fastened upon the gun-body. The gun may be of the breech or muzzle loading type so far as my invention is concerned. I have shown the inner tube A provided at the rear end with an enlargement A', in which is provided a breech-block chamber A²; but the details of the construction may vary greatly 95 without departure from my invention. At

the extreme rear end of the barrel I prefer to provide an annular cap-piece E, of solid steel, thus providing for the complete incasement of the filling material s.

5. If desired, the inner tube A may be formed with rings or a jacket t', shrunk thereon for the purpose of additional strength. In this case the inner part A would be rifled and the outer part t' externally threaded to receive 10 the sections B C. As an additional safeguard against sagging threaded perforations p may, if desired, be provided in the outer ring r, as shown in Fig. 5, through which bolts may be passed to fasten the sections together.
15. Many advantages follow from the improved construction herein shown, among which are the reduced weight of the gun itself, owing to the filling material, which may be materially lighter than steel, and the great ease with 20 which it may be taken apart and put together for transportation or replacement of parts. It is much more easy in the manufacture of the gun, also, to make the parts of uniform strength than where the entire gun is in one 25 piece. It is a comparatively easy matter to provide a tube A, either as shown in Fig. 2 or with a jacket, as shown in Fig. 4, of the maximum strength of metal throughout and to remove and replace the tube when its rifling 30 becomes worn.
35. It is believed to be entirely novel to build up a gun in such a manner that layers or concentric shells of tough and elastic steel shall be separated by sections of comparatively non-elastic shock-deadening material, whose 40 function is to preserve the outer or principal bursting-strain-resisting shell from crystallization. I therefore wish to include in my invention any construction wherein this principle is utilized, whatever material may be used for the filling, be it mineral or vegetable in its nature, and regardless of the particular manner in which the parts are constructed and put together. The filling may be made 45 in part of metal or metals combined in such a manner as to effect the useful result herein

described; but I prefer to use a non-metallic filling.

It may not be necessary to distribute the shock - deadening material throughout the 50 length of the barrel, and a modification by which the shock-deadening material extends from the breech part way of the length of the barrel will come within my invention.

While I prefer to construct my improvements throughout as shown, they may be variously modified in the matter of details of construction without departing from the spirit of my invention as defined by the claims.

What I claim as new, and desire to secure 6c by Letters Patent, is—

1. In a gun, the combination with the barrel, of metallic rings concentric with the barrel and constituting a sectional metallic shell, and intermediate sectional non - metallic 65 shock-deadening material, substantially as described.

2. In a gun, the combination with the gun-barrel of rings of metal concentric with the barrel and affording a sectional shell therefor, and disks of shock-deadening material fitting closely between the rings and barrel, and affording a sectional filling about the gun-barrel, substantially as described.

3. In a gun, the barrel comprising, in combination, an inner tube, and an outer shell secured on said tube, formed with sections, each having concentric rings of metal, and an interposed sectional filling of shock-deadening material, substantially as and for the purpose set forth.

4. In a gun, the combination in the gun-barrel, of a series of composite sections comprising inner and outer rings of steel separated by shock-deadening material, said sections being secured together longitudinally of the barrel, substantially as and for the purpose set forth.

THOMAS J. LOVETT.

In presence of—

R. T. SPENCER,
DAN W. LEE.
